UNITED STATES PATENT OFFICE.

LEWIS E. WATERMAN, OF ROCKFORD, ILLINOIS, ASSIGNOR TO EMERSON
MANUFACTURING COMPANY, OF ROCKFORD, ILLINOIS, A CORPORA-
TION OF ILLINOIS.

SEEDING-MACHINE.

No. 823,242.

Specification of Letters Patent.

Patented June 12, 1906.

Application filed January 4, 1906. Serial No. 294,643.

To all whom it may concern:

Be it known that I, LEWIS E. WATERMAN, a citizen of the United States, residing at Rockford, in the county of Winnebago and State of Illinois, have invented certain new and useful Improvements in Seeding-Machines, of which the following is a specification.

This invention relates to improvements in seeding-machines; and it consists of the cam-lever for operating the slideable section of the clutch for throwing the operative parts into or out of motion.

This invention further consists in the arrangement of the bottom of the seedbox.

In the accompanying drawings, Figure 1 is a plan view of a seedbox containing my improvements. Fig. 2 is a rear elevation. Fig. 3 is an end elevation. Fig. 4 is a transverse vertical section of the hopper. Fig. 5 is a lengthwise vertical section of one end of the seedbox and parts supported thereby. Fig. 6 is a plan view of the lower portion of one of the sections of the seedbox, and Fig. 7 is an isometrical representation of the plate or rosette 19.

The seedbox comprises the sides 1 and 2, ends 3 and 4, and a sectional bottom.

The sections forming the bottom in this instance are three in number, while in a full-sized machine a greater number are employed. The sections are all of the same construction, and a description of one will suffice. Fig. 6 shows a top view of one of these sections or cups and comprises the two edgings 5 and 6, the semicircular recess 7, the inclined surface 8 and the two end-inclined surfaces 9 and 10. The three inclined surfaces 8, 9, and 10 terminate in semicircular cavity 11.

A cut-off or follower 12 is located in a recess 7, formed in the base-section and held from rotation by the lengthwise-extending ribs 13, located in grooved ways.

45. A seed distributer or cylinder 14 has its surface provided with lengthwise-extending ribs.

50. A square shaft 15 passes through the seed-distributer 14 and the cut-off 12, and pins 16 hold the parts from movement on the shaft in its lengthwise direction. The opening in the seed-distributer is square and fits the shaft so that it will revolve with the shaft;

but the opening in the cut-off is circular, which permits the shaft to revolve within it. 55

A cap or top portion to the bottom section comprises the plate 17, beneath which the cut-off moves, and the enlarged curved section 18 which covers the seed-distributer.

A circular plate or rosette 19 has its center 60 fitted to the seed-distributer and is held from movement in the lengthwise direction of the shaft by the recess 20 in the curved projection 21, extending from the curved section 18 of the top, also by the recess 22, formed in the 65 bottom section. This plate will rotate with the seed-distributer and acts as an end to the cut-away portion 23 of the top.

From the end 4 of the seedbox extends a tubular projection 24. Within the tubular 70 projection 24 is located a bushing 25, having a rectangular opening 26, and is provided with an enlarged head 27. A spur-toothed wheel 28 has a connection with this bushing by the pin 29, passing through the hub of the 75 toothed wheel and through the bushing.

The shaft 15 is located in the rectangular opening 26 in the bushing 25, and the toothed wheel 28 will rotate the shaft.

To the outer face of the side 2 of the seed- 80 box is secured a plate 30, by the screws 31 passing through the slots 32 in the plate. An arm 33 extends from the plate and has its end 34 provided with a circular opening within which the shaft 15 may rotate. Pins 85 35 pass through the shaft and are located on either side of the end 34 of the arm 33, forming a connection between it and the shaft.

A lever 54 has a pivotal connection with the seedbox, and its lower end has a pivotal 90 connection with the plate 30.

By means of the lever 54 the plate 30 is reciprocated, which will move the shaft 15 in its lengthwise direction and carry the cut-off 12 and seed-distributer 14 with it. 95

The object in moving the seed-distributer in its lengthwise direction is to present more or less of its surface in the opening 23 in the top, so that more or less seed will be carried by it to the discharge-opening 36 in the base-section, thereby regulating the quantity of seed sown.

From the end plate 4 of the seedbox extends a tubular stud 37, which supports one end of a rod 38. This rod carries a series of 105 seed-agitators 39.

To the rod 38 is secured a toothed wheel 40, which meshes with the toothed wheel 28. The inner face of this toothed wheel is formed with a section 41 of a clutch.

5 Upon the tubular stud 37 is located a sprocket-wheel 42, which is to be driven by a belt connection with some moving part of the seeder. This sprocket-wheel has one face provided with a section 43 of a clutch, 10 and its other face has an annular groove 44.

From the end 4 of the seedbox extend two ears 45, between which is pivoted a shipping-lever 46. The lower end of this shipping-lever is in fork form, and their ends are located 15 in the annular groove 44 of the sprocket-wheel 42. The upper end of this shipping-lever is formed with a recess 47.

From the end plate 4 of the seedbox extends a stud 48, having its end screw-threaded. 20 A cam-lever 49 is supported on the stud 48 in a manner to turn thereon.

A spring 50 surrounds the stud 48 and rests against the cam-lever 49. A washer 51 is located on the stud and bears against the 25 spring 50, and a nut 52 has a screw-threaded connection with the stud.

The cam-lever 49 is located diagonally to the length of the stud 48, and its edge is received in the recess 47 in the upper end of the 30 shipping-lever.

When the cam-lever is in the position shown in Fig. 5 of the drawings, the shipping-lever will hold the clutch-sections separated in order that the sprocket-wheel may rotate 35 without rotating the toothed wheels 40 and 28 and the parts driven thereby.

By moving the cam-lever so that it will 40 engage the stop 53 the shipping-lever will be moved, so that the clutch-section carried by the sprocket-wheel 42 will engage the clutch-section carried by the toothed wheel 40, and the rotations of the sprocket-wheel will be transmitted to the toothed wheels 28 and 40 and the parts carried thereby.

45 Should the teeth 41 and 43, forming the clutch-faces, come in contact without meshing when the slideable clutch-section is moved by the shipping-lever 46, and the cam-lever 49 is thrown over against the stop 53, the cam-lever will be moved bodily in the lengthwise direction of the stud 48 against the action of the spring 50. When the teeth 43 register with the spaces between the teeth 41, the spring 50 will force the cam-lever against its 50 seat, which will move the shipping-lever, and it in turn will move the slideable clutch-section into engagement with the other section. By this arrangement of the cam-lever a more positive clutch mechanism can be employed 55 without danger of breaking the parts.

I claim as my invention—

1. In a seeding-machine, a seedbox having its bottom composed of a series of sections, each section in two planes, a seed-distributer 60 supported by each section having its upper

portion located above the lower surface of its section and means for rotating the distributors.

2. In a seeding-machine, a seedbox having its bottom composed of a series of sections, 70 each section in two planes, each section in hopper form, a seed-distributer supported by each section having its upper portion located above the lower surface of its section, and means for rotating the distributors. 75

3. In a seeding-machine, a seedbox having its bottom in sections, each section composed of a bottom plate and a top plate located in different planes, a seed-distributer and a cut-off located between the sections, the bottom 80 plate made in hopper form and terminating at the opening through which access is had to the distributor.

4. In a seeding-machine, a seedbox having its bottom in two different planes, a shaft, 85 and a series of seed-distributers supported by the shaft, having their upper portions located above the lower plane of the bottom.

5. In a seeding-machine, the combination of a seedbox, seed-distributers supported by 90 the box, means for rotating the distributors, clutch mechanism controlling the rotating means, a stationary stud, and a cam-lever mounted on the stud and having an engagement with the clutch mechanism for operating it. 95

6. In a seeding-machine, the combination of a seedbox, a shaft, seed-distributers supported by the shaft, means for rotating the distributors, clutch mechanism controlling 100 the rotating means, a stationary stud, and a cam-lever mounted on the stud having an engagement with the clutch mechanism for operating it and having a movement in the lengthwise direction of the stud. 105

7. In a seeding-machine, the combination of a seedbox, a shaft, seed-distributers supported by the shaft, means for rotating the distributors, clutch mechanism controlling 110 the rotating means, a stationary stud, a cam-lever mounted on the stud having an engagement with the clutch mechanism for operating it and having a movement in the lengthwise direction of the stud, and a spring exerting its force against the cam-lever tending to 115 hold it against its seat.

8. In a seeding-machine, the combination of a seedbox, a shaft, seed-distributers supported by the shaft, means for rotating the distributors, clutch mechanism controlling 120 the rotating means, a stationary stud, a cam-lever mounted on the stud having an engagement with the clutch mechanism for operating it and having a movement in the lengthwise direction of the stud, a spring exerting 125 its force against the cam-lever tending to hold it against its seat, and means for varying the tension of the spring.

9. In a seeding-machine, the combination of a seedbox, a shaft, seed-distributers sup- 130

ported by the shaft, means for rotating the distributor, a clutch mechanism for controlling the rotation means, comprising two clutch-faces each provided with rectangular teeth, one face slidable toward and from the other face, a shoving-lever for moving the slidable clutch-section, and yielding means for moving the shoving-lever.

5 10. In a seeding-machine, the combination of a seedbox, a tubular stud extending from

one end of the seedbox, an agitator-rod supported by the stud, a toothed wheel connected to the rod, a sprocket-wheel supported by the stud, and a clutch connection between the sprocket-wheel and toothed wheel.
